UNITED STATES PATENT OFFICE.

JOHN E. SHUTT, OF STUTTGART, ARKANSAS, ASSIGNOR TO LOUIE A. SHUTT, OF STUTTGART, ARKANSAS.

PUMP-ACTUATING MECHANISM.

Application filed March 1, 1926. Serial No. 91,599.

This invention relates to improvements in deep well pumps and is a continuation in part of my copending application filed August 26, 1925, for pump operating mechanism, Serial No. 53,181.

In a prior Patent No. 1,550,110 granted August 18, 1925, I have described and claimed a pump in which a pair of pump rods are connected to cross heads and actuated from a crank shaft by means of levers provided with fulcrums arranged above and below the crank shaft. In this device I further provide guide rods for the cross heads which extend above and below the crank shaft and receive the two cross heads.

In the present invention I provide a pump of similar construction in which the upper and lower cross heads are independently guided.

20 An object of the invention is to provide a construction in which separate guide rods are employed for the upper and lower cross heads providing a space between the adjacent ends of the guides which will permit removal of the cross head from the guide for disassembling without removing the frame.

A further object is to provide means for lubricating the guide rods and cross heads.

30 A further object of the invention is to provide a construction in which wear on the cross heads and guide rods may be compensated for by the use of shims which may be readily and easily placed in position between the cross head and the guide.

35 In the accompanying drawings I have shown one embodiment of the invention. In this showing,

Figure 1 is a side elevation, parts being shown in section,

40 Figure 2 is an end elevation,

Figure 3 is a perspective view,

Figure 4 is a plan view, parts being shown in section,

45 Figure 5 is a detail view of the lower end of one of the guide rods showing the oiling mechanism,

Figure 6 is a detail view of the center portion of the lower cross head showing the arrangement of the pump rods, and,

50 Figure 7 is a similar view of one of the cross heads disassembled.

Referring to the drawings, the reference numeral 1 designates a main shaft which is provided with a crank portion 2. This

shaft is mounted in suitable bearings formed in a pair of side members 3 forming the frame or support for the pumping mechanism and is driven from a suitable source of power by means of a gear 4 which meshes with a pinion 5 carried by a drive shaft 6. 55 As shown, the drive shaft is provided with a pulley and is adapted to receive a belt (not shown) or other suitable drive mechanism connected to a suitable source of power. Above the drive shaft I provide an upper fulcrum shaft 8 and beneath the drive shaft I provide a lower fulcrum shaft 9, each of which is supported in the frame. An upper lever 10 is mounted on the upper fulcrum shaft and a lower lever 11 is mounted on the lower fulcrum shaft. 60 As shown these levers may be in the form of bell cranks and are provided with arms 12 and 13 respectively which are slotted throughout substantially their entire lengths and are adapted to receive a roller 14 carried by the crank portion of the shaft. Each of the levers is provided with a sleeve 15 for the reception of its fulcrum. The other arm of the bell crank lever is forked at its outer end providing a pair of arms 16 (see Figure 2). 65 These arms are adapted to be connected to the forked ends 17 of links 18 by means of pins 19. The links are provided with sleeves 20 on their other ends adapted to receive a pin 21 and the ends of this pin are received in sleeves 22 carried by substantially 70 U-shaped guide members 23. The U-shaped members 23 are adapted to receive guide rods 24 which are oblong in cross section and 75 which are secured to the inner faces of the frame by means of bolts 25 or other suitable fastening elements. As shown the pin 21 is of a length slightly less than the distance between the guide rods 24. 80

Between the links 18 the pins 21 are enlarged and the lower part is provided with a threaded opening 26 adapted to receive the threaded end of a tubular pump rod 27. An inside pump rod 28 passes through the 100 lower cross head and is surrounded by suitable packing 29 retained in a packing gland formed in the cross head by means of a packing nut 30. As shown this pump rod extends upwardly and is connected to the upper cross head as at 31.

As shown the lower guide rods terminate at a point below the crank shaft and are of

5 a length sufficient to receive the lower cross head during its reciprocation. The upper guide rods are similar and of a length sufficient to receive the upper cross head during its reciprocation and the adjacent ends of the guide rods are spaced from each other. This is a material advantage as it permits 10 the removal of the cross heads and the consequent disassembling of the constriction without removing the frame by moving the lower cross head upwardly, or the upper cross head downwardly until the ends of the guide rods are reached. By providing the 15 U-shaped members 23 on the opposite sides of the cross heads and the guide rods being rectangular in cross section, taking up wear on the parts is materially simplified. As shown in Figure 5 of the drawings, shims 32 may be readily inserted between the cross head and guides for this purpose. Adjacent 20 the bottom of each of the guides I provide an oil pan 33 and the cross heads are provided with depending resilient arms 34 which are adapted to dip into these pans 25 and then contact with the sides of the guides to lubricate the guide and the cross head.

The operation of the device will be apparent from the foregoing description. The 30 rocking movement of the bell crank levers 10 and 11 caused by the movement of the roller 14 in the slotted arms 12 and 13 imparts reciprocating motion through the links 18 to the pump rods 27 and 28. The greater 35 part of the movement of one of said pump rods in either direction is accompanied by a movement of the other rod in the opposite direction.

During each revolution of the crank shaft 1, the following conditions are successively 40 created. Following the cycle from the position of the crank shaft shown in Figure 1 the lever 10 connected to the pump rod 28 is at the termination of its downward movement and about to commence its up stroke while the lever 11 connected to the pump rod 27 is approaching the end of its up stroke with decreasing speed. The up stroke of the rod 28 is then initiated with increasing speed and maximum of power application, an upward movement of pump rod 19 continues 45 until the crank shaft is at right angles to the slotted arm 13, whereupon downward movement of the pump rod 27 begins at increasing speed and decreasing power application. When the crank shaft reaches the 50 limit of its downward movement the slotted arms 12 and 13 are located opposite each other, pump rod 27 is approaching the middle of its downward movement and traveling at the greatest speed attained by it at any time during a cycle and pump rod 28 has 55 passed the middle of its upward stroke and is moving less rapidly and with greater effectiveness of power operation than rod 19. 60 65 As the crank shaft continues its revolution

in a counter clockwise direction and moves upwardly the pump rod 27 approaches the termination of its downward stroke at decreasing speed while pump rod 28 approaches the termination of its upward stroke at increasing speed. As the crank shaft passes 70 the position in which it is at right angles to the slotted arm 13 downward movement of rod 27 is changed to upward movement at increasing speed of power application and upward movement of rod 28 continues at decreasing speed until it reaches the end of its stroke when the crank shaft passes right angles to the slotted arm 12 of the upper lever. During the remainder of the stroke 80 the same mechanical principle applies as during the first half.

It will thus be seen that reversal of the direction of movement of the two rods does not take place at the same time, but at the 85 end of the stroke the two rods are moving in the same direction and thus do not reach the middle of their respective strokes at the same time. Furthermore, the two pump rods never travel at the same speed or with 90 the same effectiveness of power application except for the infinitesimal period between 95 movement of the two rods in the same direction.

It is to be understood that the form of 95 the invention herewith shown and described is to be taken as a preferred example of the same and that various changes in the shape, size, and arrangement of parts may be resorted to without departing from the spirit 100 of the invention or the scope of the subjoined claims.

I claim:

1. In a device of the character described, 105 upper and lower pivoted levers, means for oscillating said levers, a cross head connected to each of said levers, a tubular member connected to the lower cross head, a rod extending through said tubular member and said lower cross head and connected to said upper cross head, a pair of upper guide rods for said upper cross head, and a pair of lower guide rods for said lower cross head, the adjacent ends of said guide rods being 110 spaced from each other.

2. A device constructed in accordance 115 with claim 1 wherein said guide rods are provided with oiling means actuated by the movement of the cross heads.

3. A device constructed in accordance 120 with claim 1 wherein an oil pan is arranged at the lower end of each guide rod and each cross head is provided with resilient arms adapted to dip into said oil pan and engage 125 the sides of the guide rod during the reciprocation of the cross head.

4. In a device of the character described, 130 a frame comprising a pair of side members, upper and lower pivoted levers arranged between said side members, a cross head con-

nnected to each of said levers, a tubular member connected to the lower cross head, a rod extending through said tubular member and said lower cross head and connected to said upper cross head, a pair of upper guide rods secured to said frame and adapted to be engaged by said upper cross head, a pair of lower guide rods secured to said frame and adapted to be engaged by said lower cross head, the adjacent ends of said guide rods being spaced from each other.

5. In a device of the character described, a pair of upper guide rods, a pair of lower guide rods each arranged in alinement with one of said upper guide rods and spaced therefrom, a cross head reciprocable between

each pair of guide rods, and means for reciprocating said cross heads.

6. In a device of the character described, a pair of upper guide rods, a pair of lower 20 guide rods each arranged in alinement with and spaced from one of said upper guide rods, a cross head mounted to reciprocate between each pair of guide rods, a tubular member connected to the lower cross head, 25 a rod extending through said tubular member and said lower cross head and connected to said upper cross head, and means for reciprocating said cross heads.

In testimony whereof I affix my signature.

JOHN E. SHUTT.
